UNITED STATES PATENT OFFICE.

PHILIP J. BREWINGTON, OF CORPUS CHRISTI, TEXAS.

LAVATORY.

Application filed January 6, 1927. Serial No. 159,459.

The present invention relates to improvements in lavatory construction and has for its primary object to provide a lavatory constructed so as to be efficient in use and 5 extremely neat in appearance.

A further object of the invention is the provision of a lavatory designed to embody a detachable cover member adapted to enclose and conceal the water conducting and 10 drainage pipes thereof.

Still another object of the invention is the provision of a lavatory embodying a unitary structure formed with an upwardly projecting body arranged to support a 15 cabinet for the storage of toilet articles.

Another object of the invention is the provision of a lavatory of the above character which is relatively simple and durable of construction and which can be manufactured at a reasonable cost.

Other objects and advantages of the invention will become apparent as the description progresses.

In the accompanying drawings forming 25 a part of this specification and in which like reference characters are employed to designate corresponding parts throughout the same;

Figure 1 is a vertical transverse sectional view through the lavatory embodying the 30 invention,

Figure 2 is a vertical front to rear sectional view therethrough, and,

Fig. 3 is a fragmentary sectional view 35 illustrating the means provided for connecting the cover of the device detachably with the panel.

Referring to the drawings wherein for the purpose of illustration is shown the 40 preferred embodiment of my invention, the numeral 15 designates my improved lavatory structure in its entirety embodying a rectangular shaped body 16 comprising a vertically disposed supporting panel. The 45 longitudinal side edges and the top edge of the body or panel 16 are formed with a rearwardly directed flange 17 which is positioned against the wall while the lower edge rests on the floor. Thus, the panel 50 will be supported in a position spaced slightly from the wall.

Formed integral with the body or panel 55 16 and extending laterally forward at a suitable height is a basin structure embodying a wash basin 18 disposed forward of the panel and having a horizontal border

portion 19 terminating in a vertical downwardly extending apron 20. The lower central portion of the basin 18 is formed with a drain opening having a downwardly 60 extending nipple 21 adapted for connection with a drain pipe.

The lower portion of the body 16 immediately below the connection of the basin structure is formed with an inverted bell 65 shaped opening 22 arranged for the convenient extension of the water conducting pipe and the drain pipe through the panel. The upper portion of the body 16 is formed with a large rectangular opening 23 located 70 substantially above the basin connection and adapted to permit convenient installation of a toilet cabinet.

Formed integral with the body panel 16 and projecting forwardly thereof immediately below the basin connection are a pair of opposed bracket members 24 arranged adjacent the longitudinal edges of the body and substantially U-shaped in cross section. These brackets are arranged to support a 80 removable housing 25 adapted to enclose and conceal the basin pipe connections.

The housing 25 embodies a metallic, preferably enamel covered, structure substantially bell shaped at its rear side to approximately conform to the shape of the opening 22. The upper edge of the housing 25 is formed to extend about the wash basin 18 and is disposed between the basin proper and the basin apron 20. The lower portion of the housing tapers downwardly to the panel, the structure being arranged to surround the opening 22 and suitably cover the lavatory pipes. The upper inner edges of the housing 24 are formed with 95 bayonet slots 26 forming downwardly extending lugs 27 engageable with the U-shaped brackets 24. This construction permits convenient disconnection of the housing 25 when necessary, so as to permit convenient access to the pipes for making repairs.

From the foregoing description and the drawings, it will be readily noted that the present lavatory construction provides a 105 relatively high body or panel and a basin structure formed integral with the panel or secured thereto. The lower portion of the body is designed to detachably support a housing adapted to enclose and conceal 110 the pipe connections thereby permitting the use of rough unfinished pipe fittings

as well as presenting an improved appearance and protecting the pipes. The upper elevated portion of the body or panel is formed with a large opening designed to snugly receive a toilet cabinet arranged in a position, convenient for use, immediately above the wash basin. The structure therefore presents a compact and durable lavatory which may be kept in a clean and sanitary condition at all times and which may be installed without difficulty.

It is to be understood that the form of my invention herewith shown and described is to be taken as the preferred example of the same and that various changes as to the shape, size and arrangement of parts may be resorted to without departing from the spirit of the invention or the scope of the subjoined claims.

20 Suitable apertures 28 are formed in the frame for the passage of hot and cold water pipes and an aperture 29 is formed to provide an overflow.

Having thus described my invention, I claim:

1. A lavatory of the character described comprising a vertical body panel formed with an opening, a wash basin connected to the panel and projecting forwardly in a horizontal position above the opening in its lower section, and a detachable pipe housing adapted for connection with the panel below

the basin to conceal the opening therein and the pipe connections.

2. In a lavatory, a vertical support panel 35 having an opening formed in its lower portion, a basin connected with the panel and projecting forwardly thereof, a pair of U-shaped brackets upon the panel below the basin connection, and a housing detachably 40 mounted upon the panel and surrounding the opening and adapted to conceal the basin pipes, the housing being provided with downwardly projecting lugs engageable with the said brackets.

3. In a lavatory, a vertical supporting panel having an opening formed in its lower portion, a basin integral with and extending outwardly from the front of the panel and including a base body and a depending 50 apron located at the front and at the sides of said body and in spaced relation thereto, and a housing detachably mounted upon the panel and surrounding and concealing the said opening in the panel and adapted like- 55 wise to conceal the supply and drain pipes which are adapted to be extended through the said openings in the panel, the upper portion of the housing extending upwardly 60 into the space between the body of the basin and the said apron.

In testimony whereof I affix my signature.

PHILIP J. BREWINGTON.
